(57) **CLAIM**

The ornamental design for an anchor stake, as shown and described.

DESCRIPTION

FIG. 1 is a top front right perspective view of an anchor stake, showing my new design;

FIG. 2 is an oblique bottom perspective view thereof;

FIG. 3 is a front elevation view thereof;

FIG. 4 is a rear elevation view thereof;

FIG. 5 is a left-side elevation view thereof, the right-side elevation being a mirror image thereof;

FIG. 6 is a top plan view thereof;

FIG. 7 is a bottom plan view thereof; and,

FIG. 8 is a top, front, right, perspective view of the anchor stake in a state of use.

The broken lines showing a slide hammer in FIG. 8 depicts environmental subject matter that forms no part of the claimed design.
